GRINDING WHEEL DRESSER

Albert A. La Pointe, West Hartford, Conn., assignor to La Pointe Engineering Company, Unionville, Conn., a corporation of Connecticut

Application July 17, 1943, Serial No. 495,147

7 Claims. (Cl. 125—11)

1

My invention relates to devices for dressing grinding wheels such as used for grinding articles of various sorts to uniform shapes, and an object of my invention, among others, is the provision of a device for this purpose with which grinding wheels may be rapidly dressed with a maximum degree of precision.

One form of a machine embodying my invention and in the construction and use of which the objects herein set out, as well as others, may be attained is illustrated in the accompanying drawings, in which—

Figure 1 is a top plan view of the frame of a grinding machine showing my improved forming attachment applied thereto and illustrating the manner of use of the former attachment.

Figure 2 is a view in horizontal section through a portion of the machine and through my improved attachment applied thereto.

Figure 3 is a side view of the structure as shown in Fig. 2.

Figure 4 is a view in section on a plane denoted by the dotted line 4—4 of Fig. 3.

Figure 5 is a view in section on a plane denoted by the dotted line 5—5 of Fig. 3.

Figure 6 is a view in section on a plane denoted by the dotted line 6—6 of Fig. 2.

Figure 7 is an isometric view on enlarged scale illustrating my improved attachment.

Figure 8 is a similar view illustrating the carrier for the dressing tool with the dressing tool mounted therein.

Figure 9 is a similar view of the shell within which a portion of the mechanism is located and the closure for one end of the shell.

Figure 10 is an isometric view of the spindle for operating the dressing tool carrier.

Figure 11 is an isometric view of the anchoring plate for the spindle.

In the accompanying drawings the numeral 5 denotes the bed piece of the frame of a grinding machine which is commonly supported upon legs and which comprises sides 6 extending along opposite edges of the bed piece and provided with ribs 7 for the movable support of a head stock 8 and a tail stock 9 which are adjustably secured in place in any approved and desired manner, the details of which are omitted from a showing herein as they will be readily understood by those skilled in the art.

In the adaptation of my attachment as described herein the tail stock 9 is made use of by me for the support of my improved attachment, the immediate support comprising a feed

5 spindle 10 rotatably mounted in the tail stock but held against lengthwise movement therein. The tail stock is mounted upon and secured to a sliding supporting plate 11 fitted to slide upon the ribs or ways 1 which plate may be held in any position of adjustment desired as by means of screws which may be in the form of a clamping arrangement which spindle is held against lengthwise movement in the tail stock as by means of a collar 12 on the spindle located in a recess in the back of the tail stock, said recess being closed by a closing plate 13 secured to the back of the tail stock as by means of screws 14. A hand wheel 15 of the usual feed 10 wheel type is secured to the spindle as a means for operating it.

A dressing tool support 16 is secured to and extends from the inner side of the tail stock as shown in Fig. 2, this support being of generally 20 cylindrical form and having a carrier guide opening 17 extending from the end of the support adjacent to the front side of the tail stock 9 for some distance toward the opposite end of said support. A carrier guide groove 18 extends 25 along one side of said tool support from end to end and terminates at one end at the guide opening 17 as shown in Figs. 2 and 7 of the drawings. A dressing tool guide slot 19 preferably somewhat narrower than the carrier guide opening 17 extends from the bottom of the groove 30 18 inwardly into a hole 20 opening into the tool support 16 from the end thereof. In the preferred structure and as shown herein it will be noted that the dressing tool guide slot 19 extends inwardly from the carrier guide opening 17 somewhat in the form of a notch.

A dressing tool carrier 21 in the form of a bar is fitted for sliding movement in the carrier guide groove 18, a carrier guide 22 extending from one 40 end of the carrier bar 21 into the carrier guide opening 17 for movement therein, this guide having a feed screw opening 23 to receive the feed screw 10 as shown in Fig. 2 of the drawings.

A dressing tool 24 is mounted for lengthwise 45 reciprocating movement in the carrier 21 which moves it back and forth along the slot 19 in the carrier, as shown in Fig. 7, one end of this tool terminating in the hole 20.

A barrel 25 is fitted upon and surrounds the tool support 16, this barrel enclosing the dressing tool carrier 21 and being secured thereto as by means of screws 26. This barrel has a sliding movement upon the support 16 one end of its path of movement terminating adjacent the front end of 50 the tail stock 9. A screw cap 27 is fitted to close

one end of the barrel and a screw plug 28 is fitted to close a hole in the center of the screw cap.

The dressing tool 24 includes in its structure a diamond cutter terminating one end, this being of a construction common to grinding machines and which is employed for dressing a grinding wheel 29 which is rotatably supported upon the frame of the grinding machine in any well known manner and for which reason details of this support are omitted herein. A spring 30 is attached at one end to the barrel 25 and is engaged at its opposite end with the dressing tool in a manner to retain said tool in its working position. A pattern 31 is adapted to be located within the hole 20 at the end of the dressing tool support 16 and is secured in said support by a screw 32 access to which may be had through a hole closed by a screw 33 when the barrel 25 is moved to position to locate said hole opposite the screw 32. In its working position the opposite ends of the dressing tool 24 engage both the grinding wheel 29 and the pattern as shown in Fig. 2.

The head stock 8 of the grinding machine is of any well known construction not necessary for a detailed showing herein and it is provided with a chuck 34 for receiving and holding the articles 35 which are formed upon the machine, the manner of operation being as follows.

The abrading surface of the grinding wheel 29 is dressed to conform to the shape of the articles 35 to be produced by the operation of the machine, the pattern 31 being secured in the hole 20 of the dressing tool support 16 as shown in Fig. 2 and the opposite ends of the dressing tool 24 being in working engagement with the grinding wheel 29 and the pattern 31. With the parts in these positions the barrel 24 together with the parts carried thereby is given a reciprocating movement by operation of the hand wheel 15 and the dressing tool 24 moving in contact with the pattern 31 and with the grinding wheel 29 the latter has imparted to it a form corresponding to that of the pattern 31.

The grinding wheel having been properly shaped the tail stock may be moved back out of the way and the articles 35 being successively secured in the chuck 34, and the latter being rotated, the grinding wheel is moved into contact with the articles by means common to grinding machines, and as will be readily understood, and the corresponding forms to that of the grinding wheel are imparted to the articles in a particularly rapid manner and of a shape approaching perfection to a maximum extent.

It will be noted that the grinding wheel has been shown in Fig. 1 in its position for being dressed and also in position for shaping the articles, it being understood that such grinding wheel does not of course occupy these positions at the same time. As will be understood, the grinding wheel 29 may be considered as a rotative shaping element with its peripheral surface constituting a shaping face; as usual with machines of this type, the element 29 is so mounted as to be shiftable in the direction of its own axis as well as in directions normal to such axis—the two positions of the element in Figure 1 illustrates these shifting movements. Similarly, the headstock 8 is of the usual structure arranged with a rotative chuck 34 designed to carry the work 35, the chuck being power-driven; while the work is usually carried by the headstock and the tail stock, especially when the work is of extended length, in the present invention it is carried entirely by the headstock, the tail stock 9 being employed as a

support for the element dressing means. The tail stock 9 is axially aligned with the axis of the headstock 8, and is bodily shiftable rectilinearly, together with the dressing means carried thereby, in the direction of length of such aligned axes, thus making it possible to shift the tail stock toward and from the head stock at will.

In other words, the tail stock, in the present invention is made active only during the dressing of the shaping element face, while the head stock is active during the shaping of the work; during the latter period, the tail stock is maintained in an inactive position, as by shifting element 29 or shifting the tail stock thus retaining the dressing means intact, and assuring that upon restoration to active position for re-dressing of the element the shaping face of the latter will be exactly as before, thereby insuring similarity exactness of shaped work regardless of the number of pieces which may have been treated and the number of redressings required to compensate for wear in the shaping element.

The means used for preparing the face of the shaping element for its service is carried by the tail stock and made up of the various parts above described, and which may be grouped into several assemblies such, for instance, as the following: For instance, the support 16 and carrier or member 21 together with the spindle 10 and hand-wheel 15, may be considered as an instrumentality having its axis aligned with the head stock axis and designed to support the dressing tool 24 and the pattern 31 in such manner as to permit movement of member 21 rectilinearly relative to support 16 in the direction of length of such axis; since support 16 is anchored against movement relative to the tail stock and carries the pattern 31, while spindle 10 is also mounted in the tail stock in a manner to prevent movement of the spindle rectilinearly relative to the tail stock but free to rotate therein, it is apparent that the pattern 31 will be held in fixed position within the support, being movable only with the tail stock during the position-adjusting movements of the latter. The member 21, carried in the grooves of the support is held against rotation, but is capable of the rectilinear movement relative to the support through the action of the threaded zone of spindle 10, and since the member 21 carries the dressing tool 24, the inner end of the tool will traverse the pattern in the direction of length of the axis of the pattern under the manual rotation of wheel 15 and through the threaded connection between the spindle and member, the threaded connection and manual rotation of the spindle permitting a controlled movement of the dressing tool at a slow rate in such rectilinear direction.

The instrumentality is completed by the barrel or sleeve 25 which overlies and is secured to member 21—it also overlies the support 16 for a portion of the length of the latter, the sleeve partaking of the movements of member 21 and is therefore movable rectilinearly of the support. The outer end of the sleeve is closed by cap 27. The dressing tool 24 extends radially through and beyond the sleeve, the latter carrying, externally, the spring 30 which serves to not only apply inward pressure on the dressing tool but also prevents the latter from rotating as shown in Figure 9, thus preserving contact between the tool and pattern.

The instrumentality presents a number of advantages. For instance, when the pattern has been positioned in hole 20, and secured in po-

sition by screw 32, it has become definitely anchored relative to the tail stock, being carried by support 16—and since the shank of the pattern fills the open end of the hole, the active portion of the pattern is within the support. While the support formation for member 21 opens the interior of the support to the surface, this communication is closed by member 21, with the leg 22 of the latter forming a closure for the inner end of the hole 20 regardless of the movement of the member. With the sleeve 25 in position, this closed condition of the pattern chamber is further assured since the sleeve closes the side walls of groove 18 for member 21. As a result, the pattern 31 is concealed and practically sealed in a chamber into which dust, dirt, etc., cannot enter, so that the pattern surface is not affected by any accumulation of extraneous matter. Obviously it can be repeatedly used with assurance that the dressing of the shaping element will be exactly similar with each repetition of the dressing operation.

The manual feed of member 21 through the threaded connection therewith of the thread zone of spindle 10, permits the feed movement to be under the complete control of the operator with the speed of advance wholly controlled even to a very slow advance movement. As a result, the pattern may have its shaping surface of a desired type in longitudinal section—whether the surface be of straight or of sinuous contour as long as the latter is such that the dressing tool can freely advance with member 21; under such conditions assurance is had that the dressing will produce the accurate converse of the pattern contour on the shaping face of the shaping element, thus affording an exact shaping of the work to accord with the pattern contour.

The value of the above can be understood from the fact that two general conditions are present in the use of apparatus of this type, when used for the purpose of the invention. In shaping the work, dust, etc., is developed, which, if borne by air currents, will settle and provide accumulations, and, if the shaping element be a grinding wheel, wear will not only affect the diameter but where the work blank differs in general contour with the pattern, the wear on the shaping surface will not be equal, thus affecting the face; when these occur, re-dressing is in order, if exactness in product is to be maintained. Obviously, a dressing instrumentality which not only remains intact until its use has ended, and which is in the form of a unit which is practically concealed or sealed against the entrance of dust, etc., is of positive advantage, since it permits the retention of the instrumentality in the immediate neighborhood of the work-shaping position between re-dressings with no danger of the dressing being affected, thus permitting the use of the usual tail stock of the machine as a carrier for the instrumentality, even though the range of movement of the latter may be somewhat short; the advantage of the use of the tail stock as such carrier, lies in the fact that its rectilinear movements are made on fixed ways or ribs, so that each dressing operation will be at the same angle and based on the same axial alinement conditions.

I claim:

1. In machines for shaping articles, wherein the machine includes a head stock with chuck for supporting the work with the latter rotative, a tail stock axially alined with and shiftable rectilinearly relative to the head stock, and a

- 5 rotative shaping element bodily movable in the direction of length of such axis and normal to such direction to permit positioning of its shaping face relative to the positioned work to provide work-shaping activity by concurrent rotation of work and element by element movement in a direction normal to the direction of length of such axis, the combination with such machine, of means carried by the tail stock for producing 10 a shaping face on the shaping element with a radial section of the element presenting such face as in converse to the surface characteristics of the work product as presented on a diametrical section extending longitudinally of the work axis, 15 said means including an instrumentality carried by the tail stock and having a member manually adjustable in the direction of length of the tail stock axis and relative to a support carried by the tail stock and extending in axial alinement with the tail stock axis, said support carrying a removable pattern internally and axially alined with the support axis and with the pattern having its control surface conforming to the surface characteristics of the completed work surface, 20 said member carrying a dressing tool extending radially into such support and movable with the member rectilinearly of the support by the manual adjustment of the member, and a sleeve overlying the support and member and secured 25 to the member with the dressing tool extending radially through and beyond the sleeve, said tool being longitudinally movable in such radial direction under control of the pattern to thereby cause the outer end of the tool to traverse the 30 shaping element face by such manual adjustment and to dress such element face by the pattern control, whereby the dressing activities are progressive rectilinearly and during rotation of the shaping element and the shaping of the work is 35 by element adjustment in direction normal to such axis and during rotation of the work and element, and whereby the tail stock and the element shaping means in a rectilinear path is positionable in inactive position by relative movement 40 of the shaping element and the tail stock between active and inactive positions of the tail stock to permit successive dressing activities with the same pattern at will.
2. Means as in claim 1 characterized in that 45 the sleeve carries externally a spring structure co-operative with the dressing tool to prevent rotative movement of the latter and maintain contact engagement of the tool and the control surface of the pattern.
3. Means as in claim 1 characterized in that 50 the outer end of the sleeve carries a removable end closure to thereby completely enclose the pattern-carrying end zone of the support while permitting rectilinear movements of the member, sleeve and dressing tool.
4. Means as in claim 1 characterized in that 55 the member is generally of L-shaped configuration, with the longer arm carrying the dressing tool, the shorter arm having a length approximately equalling the length of the diameter of the support, and with the latter arm operatively connected with the manual operating means.
5. Means as in claim 1 characterized in that 60 the member is generally of L-shaped configuration, with the longer arm carrying the dressing tool, the shorter arm having a length approximately equalling the length of the diameter of the support, and with the latter arm operatively connected with the manual operating means, the support being grooved and channeled to receive
- 70 75

the member and permit the latter freedom for the length of its rectilinear movement.

6. Means as in claim 1 characterized in that the member is generally of L-shaped configuration, with the longer arm carrying the dressing tool, the shorter arm having a length approximately equalling the length of the diameter of the support, and with the latter arm operatively connected with the manual operating means, the support being grooved and channeled to receive 10 the member and permit the latter freedom for the length of its rectilinear movement, the free end of the sleeve carrying a removable end closure, whereby the pattern-receiving zone of the support is completely enclosed regardless of the position of the member in its rectilinear path.

7. Means as in claim 1 characterized in that the manual operating means includes a rotatable spindle supported by and extending through the tail stock, with the spindle carrying a threaded zone axially alined with the tail stock axis and co-operative with a complementary thread zone of

the member, and a hand-wheel carried by the non-threaded end of the spindle.
